CUE TIP CLAMP

Barney R. Nyhagen, New York, N. Y.

Application March 30, 1946, Serial No. 658,537

5 Claims. (Cl. 273—71)

1.

This invention has general reference to clamps and while not limited thereto the same has particular reference to an improved clamp for holding the tips on the ends of cues and the like until the adhesive which permanently secures the tips thereto has set and hardened.

The invention has in view a clamp of the indicated character which may be readily applied to the end of a cue and the like and which is adapted to be conveniently adjusted thereon to provide the desired tension on the tip.

The invention further comprehends a clamp of said character which is constructed for resilient and frictional engagement on the cue and for exerting a tension on the tip axially of the length of the cue.

The invention also has for an object the provision of a clamp which is simple in construction, inexpensive to produce and which is efficient for its intended purpose.

With the foregoing and other objects in view, reference is now made to the following specification and accompanying drawings in which the preferred embodiments of the invention are illustrated.

In the drawings:

Fig. 1 is a view in elevation of the upper portion of a cue with a clamp constructed in accordance with the invention applied thereto.

Fig. 2 is a similar view illustrating an end view of the clamp.

Fig. 3 is a top plan view of one of the members of the clamp.

Fig. 4 is a similar view of another member thereof.

Fig. 5 is a perspective view of a cue with a clamp applied thereto illustrating a modification of the invention.

Fig. 6 is a view in elevation illustrating another modification of the invention.

Referring to the drawings by characters of reference, the clamp, illustrated in the form of the invention shown in Figs. 1 to 4 inclusive of the drawings, is applied to the upper end of a cue A so as to produce a tension on the tip B thereof for temporarily holding the same thereon until an adhesive coating on the inner face of the tip hardens and sets to thereby permanently secure the tip to the cue.

The clamp comprises two members 10 and 11, having apertures 12 and 13 therethrough for slidably receiving the end of the cue for mounting the clamp thereon. The member 10 is frictionally secured on the cue by means of an elastic band 14 having leads 15 and 16 extending through

notches 17 and 18 in the member 11 and with the upper portion of the band defining a bight 19 which is trained over the tip B of the cue for temporarily holding the tip thereon until the adhesive coating on the inner face thereof hardens and sets.

The member 10 may be of any desired configuration and as illustrated the same is of rectangular formation in plan and is formed with longitudinally extending slots 20 located adjacent the opposite side edges thereof and communicating at one end with the aperture 12 so as to form a central tongue 21 between the slots 20. Mounted on the upper face of the member 10 are upstanding blocks or posts 22, one located adjacent each side edge thereof forwardly of the slots 20. Projecting upwardly and downwardly through the tongues 21 substantially central thereof is a pin 23 forming with the blocks or posts 22 abutments for receiving the member 11 therebetween in nested relation upon the upper face of the member 10 and with the apertures 12 and 13 thereof arranged in alignment so as to facilitate the insertion of the end of the cue therethrough and the engagement of the bight portion 19 of the band 14 over the tip B of the cue.

The member 11 is provided with a notch 24 in the rear edge thereof in which is received the pin 23 when said member 11 is arranged in nested relation upon the member 10. The notches 17 and 18 in the side edges thereof are located on opposite sides of the aperture 13 so that the bight portion 19 of the band 14 extends diametrically across the aperture in order to automatically position the bight portion centrally over the tip of the cue. The leads 15 and 16 of the band 14 extend downwardly through the slots 20 and thence rearwardly and upwardly through a notch 25 in the rear edge of the member 10 and then forwardly over the upper surface of the tongue 21 and down through the aperture 12 with the lower end of the band looped about the downwardly extending portion of the pin 23.

When applying the clamp to the end of a cue, the members 10 and 11 are arranged in nested relation and the cue is inserted upwardly through the apertures 12 and 13 thereof whereby the tip of the cue engages the bight portion 19 of the band 14. The member 10 is then moved downwardly on the cue so as to tension the leads 15 and 16 of the band and to dispose the member 10 at an inclination to the longitudinal axis of the cue. The canting of the member 10 on the cue by the tension of the leads 15 and 16 secures the same thereon and tensions the bight portion 19.

of the band 14 over the top of the tip with the tension thereon exerted substantially longitudinal of the cue.

In the form of the invention illustrated in Fig. 5 of the drawings, a pair of members 27 and 28 are provided corresponding to the members 10 and 11 in the previous form of the invention. In this form the member 27 is formed with an aperture 29 opening through the upper and lower faces thereof and having a connecting slot 30 opening through the rear edge thereof for receiving through said aperture the side leads 31 and 32 of an elastic band 33 which corresponds to the elastic band 14 in the previous form of the invention. The said side leads 31 and 32 extend forwardly across the lower face of the member 27 and up through the aperture 34 at the forward end thereof. The side leads then extend down through apertures 35 formed with slots 36 opening through the side edges thereof with the lower end of the band extending across the bottom face of the said member between said apertures.

The member 28 is provided with an aperture 37 adjacent each opposite side thereof which open through the opposite side edges respectively through which apertures the leads 31 and 32 extend with the upper end of the band disposed over the upper face of the member 28 diametrically of the central aperture 38 therein. As illustrated the clamp is applied to the upper end of a cue C which protrudes upwardly through the aperture 34 and 38 in the members 27 and 28 respectively to tension the band over the top of the tip D, the lower member 27 being disposed in angular relation on the cue by the upward pull of the band 33 to thereby secure the member thereon.

In the form of the invention illustrated in Fig. 6 of the drawings, the clamp consists of an annular member 39 formed with a central aperture 40 and slots 42 located on opposite sides of the central aperture which open through the side edges thereof similar to the construction of the member 28 in the previous form of the invention. An elastic band 44 is provided which is trained through the openings 42 to dispose the upper end thereof diametrically of the central aperture 40. The side leads 45 and 46 of the band extend downwardly through the slots 42 with the lower end of the band secured to a knob 47 and looped about the cue so as to form a bight to secure the same thereon. A member 43 is located in a groove in the periphery of the annular member 39 so as to retain the leads 45 and 46 in the slots 42.

As illustrated the clamp is applied to a cue E by inserting the cue upwardly through the central aperture 40 in the member 39 so as to position the upper end of the band over the top of the tip F. The lower end of the band is then looped about the cue as illustrated and the loop moved downwardly on the cue to tension the band so as to exert a tension on the tip F axially of the cue.

What is claimed is:

1. In a clamp of the character described, upper and lower members having apertures adapted to receive one end of a cue therethrough for disposing the same thereon in spaced apart relation, an elastic element secured to said lower member and having side leads extending upwardly at one end thereof, and said upper member having guides for receiving said side leads with the upper end of said elastic element trained across the aperture therein for engagement over the tip of the

cue and said lower member being adapted to be secured on the cue by the tension of the elastic element functioning to position said member at an angle to the cue with the opposite edge portions of the aperture therein impinged against the cue.

2. In a clamp of the character described, upper and lower members having apertures adapted to receive one end of a cue therethrough for disposing the same thereon in spaced apart relation, an elastic element secured to said lower member and having side leads extending upwardly at one end thereof, said upper member having guides for receiving said side leads with the upper end of said elastic element trained across the aperture therein for engagement over the tip of the cue and said lower member being adapted to be secured on the cue by the tension of the elastic element functioning to position said member at an angle to the cue with the opposite edge portions of the aperture therein impinged against the cue and said lower member having elements secured thereto in spaced apart relation and extending upwardly above the upper face thereof for receiving the upper member in nested relation therebetween upon the upper face of said lower member with the apertures in said upper and lower members disposed in alignment for facilitating the insertion of the upper portion of the cue therethrough.

3. In a clamp of the indicated character, an upper member having an aperture therethrough and notches in the opposite side edges defining guides, a lower member having an aperture extending therethrough at one end thereof and longitudinally extending slots adjacent the opposite side edges communicating at one end with said aperture, an elastic element secured to said lower member and having side leads extending upwardly through said slots at one end thereof and through said guides in the upper member with the upper end of said elastic element trained across the aperture therein for engagement over the tip of a cue and said lower member being adapted to be secured on the cue by the tension of the elastic member functioning to position said member at an angle to the cue with the opposite edge portions of the aperture therein impinged against the cue.

4. In a clamp of the indicated character, an upper member having an aperture therethrough and notches in the opposite side edges defining guides, a lower member having an aperture extending therethrough at one end thereof and longitudinally extending slots adjacent the opposite side edges communicating at one end with said aperture, an elastic element secured to said lower member and having side leads extending upwardly through said slots at one end thereof and through said guides in the upper member with the upper end of said elastic element trained across the aperture therein for engagement over the tip of a cue and said lower member being adapted to be secured on the cue by the tension of the elastic member functioning to position said member at an angle to the cue with the opposite edge portions of the aperture therein impinged against the cue and said lower member having elements secured thereto in spaced apart relation and extending upwardly above the upper face thereof for receiving the upper member in nested relation therebetween upon the upper face of said lower member with the apertures in said upper and lower members disposed in alignment for facilitating the insertion of the upper portion of the cue therethrough.

alignment for facilitating the insertion of the upper portion of the cue therethrough.

5. In a clamp of the indicated character, an apertured member having notches in the opposite side edges thereof arranged on a transverse line extending diametrically across the aperture therein, an elastic element having side leads extending through said notches with the upper end of said elastic element trained across the said aperture for engagement with the tip of a cue and means secured to the lower ends of said side leads and engaging with the cue below said ap-

ertured member for tensioning the side leads and the portion of the band trained across the aperture in said member.
